UNITED STATES PATENT OFFICE.

WILLIAM H. HEATH, OF TAUNTON, MASSACHUSETTS.

MACHINE FOR TREATING SHINGLES.

SPECIFICATION forming part of Letters Patent No. 406,045, dated July 2, 1889.

Application filed November 1, 1888. Serial No. 289,770. (No model.)

To all whom it may concern:

Be it known that I, WILLIAM H. HEATH, of Taunton, county of Bristol, State of Massachusetts, have invented an Improvement in 5 Machines for Treating Shingles, of which the following description, in connection with the accompanying drawings, is a specification, like letters on the drawings representing like parts.

10 This invention has for its object to provide a machine for smoothing or finishing shingles such as commonly employed in the construction of houses.

In accordance with my invention the shingle is subjected to the cutting action of a knife or knives on one or both its sides, according to the kind of shingle treated—that is, whether the same has been split or sawed from the log—the said knife or knives being 20 moved from the butt to the tip of the shingle in converging guides to conform to the tapering form of the shingle.

Another feature of my invention consists in mechanism by which the movement of the 25 knife is automatically stopped after it has acted upon the shingle, as will be hereinafter described.

My invention therefore consists, essentially, in the combination, with a knife to trim the 30 surface of the shingle, of a guide and a carrier for said knife, a main shaft, a counter-shaft provided with a clutch driven from the main shaft and adapted to rotate the counter-shaft, and a shipper mechanism connected to said 35 clutch to move the said knife over the surface of the shingle on the rotation of the said shaft, substantially as will be described.

Other features of my invention will be pointed out in the claims at the end of this 40 specification.

Figure 1 is a side elevation of one form of machine embodying my invention; Fig. 2, a longitudinal section, partially broken out, of a sufficient portion of a machine to enable it 45 to be understood, the section being taken on line $x-x$, Fig. 3; Fig. 3, a top or plan view of the machine shown in Fig. 1; Fig. 4, a rear end elevation of the machine shown in Fig. 3; Fig. 5, a section of a modification to be referred to, the section being taken on line $y-y$, Fig. 6; and Fig. 6 a top or plan view of part

of the mechanism shown in Fig. 5; Fig. 7, a detail to be referred to; Fig. 8, a detail in elevation of the jaws; and Fig. 9, a sectional detail to more clearly show the guides for the 55 knives.

The frame A, of sufficient strength to sustain the working parts, supports in suitable boxes a , secured, as shown, to the rear side of the frame, a main shaft a' , provided with 60 the usual driving-pulley a^2 . The main shaft a' has mounted upon it a pinion a^3 , which meshes with and drives a gear-wheel a^4 on a shaft a^5 , supported in suitable bearings a^6 , (see Fig. 4,) the said gear-wheel constituting 65 part of a clutch mechanism, to be described.

The gear-wheel a^4 is provided, as herein shown, with an elongated hub a^7 , having at one side of the said gear an annular groove a^8 , which is engaged by forked arms a^9 of a 70 rod a^{10} , (see Fig. 2,) herein shown as secured to a bar a^{12} , pivoted to the frame A by a threaded bolt a^{13} , the said bar forming a part of the shipper mechanism, it being connected, as herein shown, by rod a^{14} to bar a^{15} , pivoted, 75 as at a^{16} , (see Fig. 3,) to a bracket a^{20} , secured to a cross-bar a^{21} of the frame A, the bar a^{15} being connected by a link or bar a^{16} (see Figs. 3 and 4) to the shipper-lever a^{17} , pivoted to the frame, as at a^{18} . The hub a^7 , on the other 80 side of the gear-wheel a^4 , is provided with a shoulder a^{25} , (see Fig. 4,) to engage a shoulder a^{26} on a hub or collar a^{27} , fast on the shaft a^5 , the said shaft being rotated when the shoulder a^{25} on the hub engages the shoulder a^{26} on 85 the hub a^{27} in the rotation of the gear-wheel.

The shaft a^5 has mounted upon it, as herein shown, within the sides of the frame A at its opposite ends, two disks b b' , provided with crank-pins b^2 b^3 , to which are connected one 90 end of links b^4 b^5 , secured at their opposite ends to levers b^6 b^8 , pivoted to the frame of the machine, as at b^9 , the said levers constituting carriers for one or more knives b^{10} , having their ends inserted through slots b^{12} 95 in the said levers and bent to form arms b^{20} , which are fitted into guideways b^{13} b^{14} , (see Fig. 2,) secured to the sides of the frame.

The guideways b^{13} b^{14} are made inclined from the rear toward the front end of the machine, so that as the knives are moved forward, through their carriers and links con- 100

nected to the disks on the shaft a^5 , the said knives will gradually converge or approach each other, and thus conform to the tapering form of the shingle, whereby the latter, with 5 the machine shown in Fig. 2, is smoothed or finished on both faces at the same time.

In operation, when both sides of the shingle b^{15} are to be smoothed or finished, as will be the case with a split shingle, the said shingle 10 is inserted between the knives b and has its rear end or butt gripped between jaws c c' , the jaw c being herein shown as rigidly secured to the frame, (see Fig. 2,) and the jaw c' pivoted, as at c^2 , and connected at its rear end 15 by rod c^3 to a foot treadle or lever c^5 , pivoted or suspended, as at c^6 , said treadle having its front end extended through a slot c^7 in a bracket c^8 , (see Fig. 1,) secured to the frame A, and provided with a notch to form a lock 20 for said lever, the said treadle having connected to it, as shown, one end of an elevating-spring c^9 , by which the lever c^5 , when disconnected from a notch in the bracket c^8 , is raised to unclamp the lower jaw c' , when it is 25 desired to remove a shingle from between the jaws—that is, after the said shingle has been finished—the treadle c^5 being engaged with the notch, as shown in Fig. 1, when the shingle has been placed in position to be operated 30 upon.

The front or tip end of the shingle will be supported in suitable manner—as, for instance, in a notch d in a bar d' , secured to the frame A.

35 In order that the knives may be automatically stopped when brought to their normal or starting position, as shown in Fig. 2, after having finished a shingle, the shipping mechanism is automatically operated to disengage 40 the clutch portion of the hub a^7 from its cooperating portion a^{27} , fast on the shaft a^5 . To accomplish this result, the disk b is provided, as herein shown, on its periphery with a stud or pin e , (see Fig. 3,) which acts upon the end 45 of a locking-bar e' , (see Figs. 1, 4, and 7,) secured, as by bolt e^2 , to the bar a^{12} of the shipping mechanism, the said bolt, as herein shown in Fig. 4, being extended through a slot in the said bar to permit of vertical movement 50 of the said bar, the bar e' having its front end shouldered, as at e^3 , to engage a notch e^4 in a plate e^5 , secured to the frame A, (see Fig. 3,) and to lock the shipping mechanism in operative position, the said shoulder being thus 55 engaged with its notch when the shoulder a^{25} of the hub a^7 is engaged with the shoulder a^{26} of the hub on the shaft.

In order that the movable jaw c' may be loosened automatically after the shingle has 60 been finished, the bar a^{15} is provided, as herein shown, with a projection e^8 , (see Fig. 1,) which acts against the lever c^5 and disengages it from its notch in the bracket c^8 , thereby permitting the spring c^9 to elevate 65 the said lever, and through it to disengage the movable jaw.

In some instances it may be desired to stop

the machine at any part of the travel of the knives; and for this purpose I have provided a lever f , (see Fig. 1,) having one end extended 70 beneath and in line with the projecting end of the bar e' , the other end of the lever f having secured to it a rod f' , herein shown as extended through a suitable guide f^2 , (shown as a staple,) and provided above the frame of the 75 machine with a handle f^3 , so that by depressing the rod f' the lever f may be turned on its pivot f^4 to bring its free end into engagement with the bar e' and raise its shoulder e^4 from the notch e^4 , thus permitting the spring 20, 80 secured to the bar a^{15} of the shipping mechanism, to disengage the hub a^7 of the gear from the hub on the shaft.

When the shingle to be treated is what is known as a "sawed" shingle, one of the 85 knives may be dispensed with, preferably the lower one, and the upper knife employed to act on or trim the upper surface or face of the shingle, the latter in this case being sustained in correct position by a supporting frame or 90 bed, (shown as a board or plate g ,) provided with arms g' , which rest upon ledges or shoulders g^2 (see Fig. 3) on the sides of the frame.

The inner end of the supporting frame or 95 bed is secured between the jaws c c' , and the shingle is secured to the said bed, as herein shown, by a stud or pin g^4 , (see Fig. 6,) having a sharpened point to pierce the shingle.

I claim—

1. In a machine for treating shingles, the combination, with a knife, of a guide inclined from one toward the opposite end of the machine and in which the said knife travels, levers on opposite sides of the machine, to which the said knife is secured, and jaws to hold 105 one end of the shingle, a main shaft, a counter-shaft provided with a clutch driven from the main shaft and adapted to rotate the counter-shaft, and a shipper mechanism connected to said clutch, substantially as described.

2. In a machine for finishing shingles, the combination, with knives, of converging guides in which the said knives travel, carriers for said knives, and jaws to hold one end 115 of the shingle, a main shaft, a counter-shaft provided with a clutch driven from the main shaft and adapted to rotate the counter-shaft, a shipping mechanism connected to said clutch, and a stop carried by the counter-shaft 120 to act on the shipping mechanism and automatically disengage the clutch to stop rotation of the counter-shaft, and thereby travel of the knives, substantially as described.

3. In a machine for finishing shingles, the combination, with knives, of converging guides in which the said knives travel, carriers for said knives, and jaws to hold one end 125 of the shingle, a main shaft, a counter-shaft provided with a clutch driven from the main shaft and adapted to rotate the counter-shaft, and a shipping mechanism connected to said clutch, a locking-bar secured to the shipping mechanism, a lever f to act on said bar to dis-

engage the shipper mechanism to stop the travel of the knives, substantially as described.

4. In a machine for finishing shingles, the combination, with knives, of converging guides therefor and carriers for said knives, a fixed jaw and a movable jaw to hold the shingles, and a lever, as c^5 , connected to the movable jaw, a lock for said lever, a main shaft, a counter-shaft provided with a clutch driven from the main shaft and adapted to rotate the counter-shaft, a shipping mechanism connected to said clutch, a stop carried by the counter-shaft to act on the shipping

mechanism and automatically disengage the clutch to stop rotation of the counter-shaft, and a projection on the shipping mechanism to act on the lever connected to the movable jaw and release the said lever, substantially as and for the purpose specified. 15 20

In testimony whereof I have signed my name to this specification in the presence of two subscribing witnesses.

WILLIAM H. HEATH.
